[57] CLAIM

The ornamental design for a bed, as shown and described.

DESCRIPTION

FIG. 1 is a perspective view of a bed, showing our new design, the broken line being for environmental purposes only and form no part of the claimed design; FIG. 2 is a side view thereof;

FIG. 3 is a right-front view of FIG. 2;

FIG. 4 is a left-rear view of FIG. 2;

FIG. 5 is a front perspective view of the headboard insert, the footboard insert being omitted for convenience of illustration;

FIG. 6 is a front view thereof;

FIG. 7 is a left-side view thereof;

FIG. 8 is a rear view thereof;

FIG. 9 is a front perspective view of the footboard insert, the head board insert being omitted for convenience of illustration;

FIG. 10 is a rear view thereof;

FIG. 11 is a left-side view thereof;

FIG. 12 is a front view thereof;

FIG. 13 is a front perspective view of the headboard insert of an alternate embodiment of the bed of FIG. 1, the footboard insert being omitted for convenience of illustration; and,

FIG. 14 is a front view thereof.
